[57] CLAIM

The ornamental design for a scented air filter, as shown and described.

DESCRIPTION

FIG. 1 is a front, top and side perspective view of the scented air filter showing my new design;

FIG. 2 is a front elevational view thereof, the rear being a mirror image of the front shown in FIG. 2;

FIG. 3 is a side elevational view thereof, the side opposite being a mirror image of the side shown in FIG. 3; and,

FIG. 4 is a top plan view thereof, the bottom being a mirror image of the top.

FIG.1

FIG. 2

FIG. 3

FIG. 4
